COIL EXCITED VIBRATOR ASSEMBLAGE
Floyd E. Smith, 3430 Glenside Ave., Erie, Pa.
Filed Jan. 11, 1963, Ser. No. 250,835
14 Claims. (Cl. 310—28)

This invention relates to a vibrator assemblage of the electro-magnetic type for use in vibrating objects as required in various processing operations.

Under certain operating conditions, it is desired to have high intensity vibrations, even though available vibrator space is limited. Accordingly, it is an object of the invention to provide an electro-magnetic type vibrator wherein high intensity vibrations are attainable with a relatively small and compact vibrator assemblage. Such an object is realized by arranging a major portion of the vibrator mass, as the vibrating body. More particularly, the lamination stack, coil and a relatively heavy cover plate for the stack, are included in the vibratory mass portion of the vibrator. The weight ratio percentage-wise of said vibratory elements and the overall weight of the vibrator assemblage, is preferably above 50%.

Among other features desirable in a vibrator of the type under consideration, is a provision for adjusting the vibration intensity within a given range. While such adjustment can be made with an input power regulator, such as a rheostat, a built-in intensity adjustment means enhances the commercial attractiveness of a vibrator. Accordingly, a further object of the invention is the provision of a simple means for adjusting the intensity of vibrations in a rapid and convenient manner. Toward this end, a pair of adjusting screws are provided which may be used to accomplish such adjustment, without the need for disassembly of the vibrator and while it is in a given operative position. Very accurate adjustment is thus attainable. Such adjustment means also eliminates the need for factory adjustment, which makes for a custom-built type of manufacturing operation insofar as customer specifications vary according to contemplated usage, or operative limits.

A further feature desired in a vibrator of the subject type, is the protection of the working parts against dust or dirt. Hence, another object is the provision of means for insuring that the interior of the vibrator will be completely sealed against contamination by dust, dirt, or other deleterious substances. A totally enclosing cover is provided for attainment of such an object, which cover may be readily applied, and/or removed as the case may be.

Further objects are to provide an electro-magnetic type of vibrator which is of simple design, of rugged construction, and which will provide long and trouble-free service.

These and further objects and features of the invention will become more apparent from the following description and accompanying drawings wherein:

FIG. 1 is an exploded perspective-like view of a vibrator assemblage illustrative of an embodiment of the invention;

FIG. 2 is an enlarged vertical section view of the vibrator assemblage of FIG. 1;

FIG. 3 is a section view, on a reduced scale, as seen from line 3—3 in FIG. 2;

FIG. 4 is a plan view of a base plate used in the vibrator assemblage of FIG. 1;

FIG. 5 is an edge view of same;

FIG. 6 is a plan view of an armature used in the vibrator assemblage of FIG. 1;

FIG. 7 is an edge view of same;

FIG. 8 is a plan view of a compression ring used in the vibrator assemblage of FIG. 1; and

FIG. 9 is a vertical section view of a rubber spring of a post assembly used in the vibrator assemblage of FIG. 1.

FIGS. 3 to 8 inclusive have been drawn in full scale

2

to indicate a vibrator size which has had successful commercial application.

Referring now to the drawings, numeral 10 identifies a vibrator assemblage embodying the principles of the invention, which includes a base plate 12, an armature 14, a plurality of post assemblies each formed of a rubber spring 16 and a spacer 18, a core and coil assembly 20 affixed to a top plate 22, and a cover 24.

The base plate 12 is of generally rectangular shape, and is formed with two circular recesses 26, on the upper surface of the plate which are symmetrically arranged relative to the midpoint thereof, as best seen in FIG. 4. A pair of holes 28 are formed in the plate 12, each of the holes coinciding with the center of a respective recess 26, and having a counter bore 30 at the lower end, whereby a recessed head, cap screw 32 may be arranged for threaded engagement with holes 33, formed in the armature 14. The armature which has an elongated rectangular shape, is positionally supported upon the base plate 12 by a pair of rubber O rings 34, each being seated in a recess 26. The major diameter of each ring 34, is preferably equivalent to the diameter of its seating recess 26. By rotating the cap screws 32, the armature 14 may be positioned a variable distance relative to the base plate 12, for reason of which will become more apparent hereinafter. A post mounting means in the form of a threaded hole 36 is provided in the geometrical center of the base plate 12, for receipt of a post, or rod 38, whereby the vibrator 10 may be mounted upon an object, or surface (not shown) to be vibrated. The post is long enough to provide clearance for a wrench so that the screws may be rotated as required in an adjusting operation. Four threaded holes 40 are symmetrically arranged in the base plate 12 for receipt of the rubber springs 16. As best seen in FIG. 3, the rubber springs 16 are positioned to provide ample clearance for the armature 14. Threaded holes 42 are formed in opposite sides of the base plate 12 for receipt of screws 44 which pass through holes 46 in the cover 24 whereby the latter may be removably affixed to the base plate.

The core and coil assembly 20 includes a plurality of E-shaped laminations 48, forming a lamination stack which is secured, such as by welding, to an assembly plate 50, and a coil 52. The lamination stack is substantially equal in width to the width of the armature 14. The coil is wound with wire as required for attainment of desired operation or performance characteristics, as is well within the knowledge of electrical engineers, and others skilled in the art. For example, one operative model designed for 115 volt, 60 cycle operation, at 10 watts, had 3,000 turns of No. 35 wire. The assembly plate 50 is sandwiched between the top plate 22 and the spacers 18, and secured to the spacers by fastening means such as recessed head cap screws 54, passing through recessed holes 56 formed in the top plate. A grommet 58, positioned in a hole formed in a side wall of the cover 24, provides an insulated outlet for lead wires (not shown) connected to the coil 52.

The rubber spring 16 used in each of the post assemblies is formed of a rubber cylindrical piece 60 having a flat headed stud 62 bonded to each end, as best seen in FIG. 9.

A magnetic flux path is formed by the laminations 48 and the armature 14, which path includes an adjustable gap 64 disposed between the end of the laminations and the upper surface of the armature. Adjustment of the gap dimension 64 by means of the screws 32, will vary the vibration amplitude to a degree as desired within the operative range of the vibrator. It will be seen that the rubber O rings 34 will resiliently support the armature 14 in adjusted position so that the position of adjustment will be maintained. Amplitude adjustment may thus be

made with the vibrator operatively mounted upon the object to be vibrated, which provides great convenience for final adjustment at point of use.

The materials required in the formation of various parts of the vibrator assemblage 10, may vary according to design specifications. By way of example, the armature 14 may be of Armco ingot iron, the base plate 12 and top plate 22 of cold rolled steel, the laminations of Webcor W-50 steel, the spacers 18 of $5/16$ " hex. brass, the O rings 34 of Buna-N" rubber, the rubber springs 16 as in Lord shock mountings, and the cover 24 being made of aluminum. For sixty cycle operation, the rubber springs 16 preferably have a Durometer rating of about 65; for lower frequency operation, a softer rubber may be desirable, such as a Durometer rating of 50, at fifty cycle current.

Since the size of the major vibratory parts are important for attainment of the stated objectives, it has been found that a top plate 22 having dimensions of approximately $1\frac{1}{16}$ " square by $\frac{3}{8}$ " thick, and a lamination stack having overall dimensions of $1\frac{5}{8}$ " x $1\frac{1}{16}$ " x $\frac{5}{8}$ ", and a wire coil as hereinbefore specified, will provide a high magnitude vibratory output coupled with small vibrator size. As will be readily apparent, the mass of the lamination and coil assembly 20, as well as the relatively heavy cover plate 22, and the post assembly spacers 18 all of which form at least fifty percent of the total weight of the vibrator 10, will be applied in an alternating manner to the base plate 12 via the post assemblies, so that a vibratory force of great magnitude will be generated with a comparatively small size vibrator assemblage. Note that the armature adjustment means, i.e., screws 32, allows greater dimensional tolerances of certain parts, because final adjustment may be made on the vibrator after assembly, and in operative position if desired, to provide optimum operation thereof.

It will be seen that a vibrator assemblage made as above described will satisfy all of the objectives set forth hereinbefore.

The foregoing description has been given in detail without thought of limitation since the inventive principles involved are capable of assuming other forms without departing from the spirit of the invention or the scope of the following claims.

What is claimed is:

1. A vibrator assemblage comprising in combination, a base plate, an armature, a pair of rubber rings compressively disposed between the armature and base plate, a lamination stack secured to a top plate, a coil arranged on the lamination stack, a plurality of post assemblies for mounting the top plate to the base plate with an air gap between the end of the lamination stack and the armature, and means to adjust the position of the armature relative to the base plate.

2. A vibrator assemblage comprising in combination, a base plate, an armature, a pair of resilient rings arranged for compressive mounting between the armature and the base plate, a lamination stack secured to a top plate, a coil arranged on the laminations, a plurality of post assemblies for mounting the top plate to the base plate with an air gap between the end of the lamination stack and the armature, said post assemblies each including a resilient section, and a pair of adjusting screws seated in the base plate and threadably engaging the armature whereby the armature may be adjustably positioned relative to the base plate.

3. A vibrator assemblage according to claim 2, wherein a cover is adapted to enclose the elements of the assemblage.

4. A vibrator assemblage according to claim 2, wherein the resilient rings are formed of rubber.

5. A vibrator assemblage according to claim 4, wherein the post assembly resilient section is formed of rubber.

6. A vibrator assemblage comprising in combination, a generally rectangular base plate, an elongated rectangular armature, a pair of rubber rings disposed between the

armature and the base plate and symmetrically arranged relative to the armature, a lamination stack secured to a top plate, a coil arranged on the laminations, a plurality of post assemblies one each being positioned in a corner

5 region of the base plate and connecting the cover plate to the base plate with an air gap between the end of the lamination stack and the armature, and a pair of adjusting screws seated in the base plate, and rotatable from the exterior surface of the base plate, said screws each extending through a respective rubber ring and threadably engaging the armature.

7. A vibrator assemblage according to claim 6, including a cover which is removably affixed to the base plate and is arranged to enclose the other elements of the 15 vibrator assemblage.

8. A vibrator assemblage according to claim 6, wherein each of the post assemblies includes a cylindrical rubber portion.

9. A vibrator assemblage according to claim 6, wherein 20 the base plate is formed to provide recesses for seating the rubber rings.

10. A vibrator assemblage according to claim 6, wherein in a post mounting means is provided in the geometrical center of the base plate.

25 11. A vibrator assemblage according to claim 6, wherein in a post mounting means comprises a threaded hole.

12. A vibrator assemblage comprising in combination, a base plate, an armature, resilient means compressively disposed between the armature and base plate, a lamination 30 stack secured to a top plate, a coil arranged on the lamination stack, a plurality of post assemblies for mounting the top plate to the base plate with an air gap between the lamination stack and the armature, and means to adjust the position of the armature relative to the base plate, 35 said lamination stack and coil assembly forming at least fifty percent of the total weight of the vibrator assemblage.

13. A vibrator assemblage comprising, in combination: a base plate; resilient means; an armature fixedly and adjustably secured to said base plate with said resilient 40 means compressively disposed therebetween; a lamination stack and coil assembly resiliently mounted upon the base plate so as to impart a vibratory action to said assemblage, said stack being spaced from said armature to form an air gap therebetween and said armature being positionably adjustable to vary the air gap between said stack and 45 said armature to vary the intensity of the vibratory action imparted to said assemblage by said lamination stack and coil assembly.

14. A vibrator assemblage comprising, in combination: 50 a base plate; resilient means; an armature; adjusting means for fixedly and adjustably securing said armature to said base plate with said resilient means compressively disposed therebetween; a lamination stack and coil assembly resiliently mounted upon the base plate so as to 55 impart a vibratory action to said assemblage, said stack being spaced from said armature to form an air gap therebetween and said adjusting means being operable to positionably adjust said armature to vary the air gap between said stack and said armature to vary the intensity 60 of the vibratory action imparted to said assemblage by said lamination stack and coil assembly.
